UNITED STATES PATENT OFFICE

159,535

JACKET-TYPE COASTER

Aileen M. Reineke, Cary, Ill.

Application November 17, 1948, Serial No. 149,685

Term of patent 14 years

(Cl. D44—10)

To all whom it may concern:

Be it known that I, Aileen M. Reineke, a citizen of the United States, residing at Cary, in the county of McHenry and State of Illinois, have invented a new, original, and ornamental Design for a Jacket-Type Coaster, of which the following is a specification, reference being made to the accompanying drawing, forming a part thereof, in which

Fig. 1 is a perspective view of a coaster embodying my new design;

Fig. 2 is a side elevational view of the same; and
Fig. 3 is a top plan view thereof.

I claim:

The ornamental design for a jacket-type coaster, substantially as shown.

AILEEN M. REINEKE.
